UNITED STATES PATENT OFFICE.

THOMAS W. COULSON AND PETER C. DODENHOFF, OF DETROIT, MICHIGAN.

DESIGN FOR A COVER FOR LEATHER PILLOWS.

No. 38,296.

Specification for Design.

Patented Oct. 23, 1906.

Application filed May 2, 1906. Serial No. 314,901. Term of patent 3½ years.

To all whom it may concern:

Be it known that we, THOMAS W. COULSON and PETER C. DODENHOFF, citizens of the United States of America, residing at Detroit, in the county of Wayne and State of Michigan, have invented a certain new, original, and ornamental Design for Leather Covers for Pillows, of which the following is a specification, reference being had therein to the accompanying drawing.

The figure is a plan view of a pillow-cover, showing our new design.

We claim—

The ornamental design for a leather cover for a pillow as shown.

THOMAS W. COULSON.
PETER C. DODENHOFF.
